(57) CLAIM

The ornamental design for a fastener driver accessory as shown and described.

DESCRIPTION

FIG. 1 is a front perspective view of a fastener driver accessory according to a first construction.

FIG. 2 is a rear perspective view of the fastener driver accessory of FIG. 1.

FIG. 3 is a right side view of the fastener driver accessory of FIG. 1.

FIG. 4 is a left side view of the fastener driver accessory of FIG. 1.

FIG. 5 is a top view of the fastener driver accessory of FIG. 1.

FIG. 6 is a bottom view of the fastener driver accessory of FIG. 1.

FIG. 7 is a front view of the fastener driver accessory of FIG. 1.

FIG. 8 is a rear view of the fastener driver accessory of FIG. 1.

FIG. 9 is a front perspective view of a fastener driver accessory according to a second construction.

FIG. 10 is a rear perspective view of the fastener driver accessory of FIG. 9.

FIG. 11 is a right side view of the fastener driver accessory of FIG. 9.

FIG. 12 is a left side view of the fastener driver accessory of FIG. 9.

FIG. 13 is a top view of the fastener driver accessory of FIG. 9.

FIG. 14 is a bottom view of the fastener driver accessory of FIG. 9.

FIG. 15 is a front view of the fastener driver accessory of FIG. 9; and,

FIG. 16 is a rear view of the fastener driver accessory of FIG. 9.

The portions of the fastener driver accessory shown in broken lines are included for the purpose of illustrating environment and form no part of the claimed design. The portions of the fastener driver accessory shown in broken

lines having unequal length segments illustrate the boundary of the claimed design and form no part of the claimed design.
